UNITED STATES PATENT OFFICE

2,605,511

TAKING-OFF OF WEBS OR FLEECES FROM
SMOOTH ROLLERSLawrence Crowther, Pudsey, England, assignor
to Hubert Duesberg, Heusy-Verviers, BelgiumApplication February 18, 1947, Serial No. 729,276
In Great Britain February 28, 1946

4 Claims. (Cl. 19—67)

1.

This invention relates to the taking-off of fibre webs or fleeces from smooth rollers such for example as those used for crushing foreign substances or bodies in the treatment of thinly spread out webs especially as disclosed in U. S. Patent No. 2,075,156.

Hitherto it has been customary to deliver the web or fleece from between the crushing rollers onto an endless band or lattice mounted close to the rollers and driven at a speed approximating the surface speed of the crushing rollers. Certain materials, instead of passing freely off the delivery end of the lattice, tend to adhere thereto and may also adhere to the crushing rollers. Furthermore, in the interest of efficient crushing, the web must be made very thin. However, the thinner the web the greater will be the effect of static electricity and the more will the web adhere to lattice and rollers. Also, such an arrangement will cause a thin band or sliver to be formed from the thin web and such a thin band or sliver is difficult to convey to another machine for further processing, due to its lack of strength and consistency.

According to the present invention a fibre web is removed from a smooth faced roller by means of a doffing roller clothed with wire teeth and rotating in a direction and at a relative speed that ensures a condensing or thickening action on the web before it is removed by stripping means. The doffing roller is covered with card clothing or its equivalent.

The doffing roller can be set in close proximity to the lower of a pair of crushing rollers in such a position that the web is allowed to adhere to said lower roller for a given distance before being removed by the doffing roller. The latter may have the ends of the wire teeth of the card clothing set in such a way that these are rearwardly inclined from their direction of rotation so that fibres of the web are forcibly pushed between the wire teeth to be carried round to the stripping point.

Referring now to the accompanying drawings in which an embodiment of this invention is shown by way of example:

Fig. 1 is a side view of crushing apparatus for treating textile webs of fibres with the improved device associated therewith;

Fig. 2 is a plan view of Fig. 1;

Fig. 3 is a side view of the crushing rollers with the feeding and doffing rollers.

In one embodiment of the invention, as applied to the apparatus disclosed in the aforesaid patent, the thinly spread out web 1, produced on a carding engine and passed between the two superposed crushing rollers 2, 3, is removed from

2.

the lower crushing roller by a doffing roller 4. The latter is covered with card clothing whose wires have their tips inclined rearwardly relative to the direction of rotation of the doffer roller. The latter rotates in the opposite direction to that of the adjacent crushing roller 3, and at the same or a less speed than such roller. The doffing action takes place at a desired point (e. g., level with the axis of the crushing roller) after the web has passed partially around the lower roller from the nip of the two rollers. The wires of the doffing roller stop or obstruct the fibres of the crushing roller and thus the fibres are pushed between such wires to be carried round by the doffer for a given distance to a stripping point. The speed of the doffer and its arrangement is such that the thin web is caused to become more condensed or thickened and thus when stripped off can produce stronger slivers or bands for conveyance to the next process. The doffing roller may be driven in any convenient manner and its speed may be variable at will. In the construction shown the doffing roller is driven from the pulley 5, on shaft 6, through means of the gear wheels 7, 8, 9 and 10. Gear wheel 7 is mounted fixedly on the shaft 6 of the crushing roller 3 whilst the gear wheel 8 is carried by a stud 11 mounted in the carrier plate 12 which is secured to the main frame 13 of the apparatus. The gear wheel 9 is carried by an arm 14 which is pivoted on the stud 11 so that it can be released for the wheel 9 to be swung out of engagement with gear wheel 10 for the latter to be changed when a change of speed is desired.

The doffing roller can be mounted in any convenient manner and in the drawings is shown with the ends of its shaft 15 mounted in end bearings 16 which are carried slidably on horizontal rods 17. The latter are supported in fixing brackets 18 and screw threaded to receive adjustable lock nuts 19 which hold the bearings 16 in an adjusted position when the doffing roller has been set to its desired position relative to the roller 3. In this manner the doffing roller can have a fine setting for deciding the depth of penetration of the fibres into the wires on the doffing roller to suit the thickness and type of web being crushed.

50 The web is stripped from the doffer in any convenient manner, e. g., by means of a known form of fly comb 20 whose shaft 21 is mounted on the needle bearer shafts 22 of the end bearings 23 which are adjustably locked in position 55 on the forehead rods 17 by lock nuts 24. The comb is driven from the pulley 5 on the roller shaft through belts 25, 26, multi-pulley 27

mounted freely on shaft 15 and twin pulley 28 which oscillates the shaft 21 through the usual mechanism 29.

If so desired the fly comb may be replaced by some form of stripping device such as a small roller having card clothing as used on the fancy of a carding engine and rotating in the same direction as the doffer. Alternatively, a rotatable element having beater blades could be used. The speed of operation of either of these devices may be adjustable. Drafting means could be used to facilitate the removal of the web.

The web of fibers detached from the doffing roller can be delivered on to any form of conveyor, e. g., side or central draw, ball and bank feed, parallel fibre feed or the like. Moreover, the aforesaid doffing roller could be in another position to that before described, e. g., the axis of the roller could be in the same plane as the nip of the superposed rollers and may even take fibres off the upper smooth roller.

Furthermore, it is known that the web detached from the doffer of a carding engine is led by means of a lattice or a tin roller to the nip of the aforesaid crushing rollers 2, 3, or other smooth rollers. However, if the web is very thin such conveyor means are not sufficient to keep the fibres under proper control and in addition both the lattice and the tin roller may become soiled by oil, and consequently the thin web will stick to them and break. The present invention is intended also to overcome these difficulties and to make the entrance side as near foolproof as is possible, so that it does not need attention on the part of the operator. It is proposed to substitute for the lattice or tin roller a pair of conveyor rollers, 34, 35, of small diameter.

These rollers are covered by ordinary card clothing (filets) of the normal wire density of carding machine stripper rollers, both revolving in the same direction as the bottom roller 3, of the crushing apparatus and the wire ends are arranged to be pointing opposite to the direction of motion. The conveyor roller 34 next to the crushing roller is set near to it and the second roller 35 is almost touching the first. Their surface speed is slightly less than that of a crushing roller 3. The web stripped from the carding doffer is simply dropped on to these conveyor rollers and they carry it automatically to the nip of the crushing rollers without further attention being given to them. The two conveyor rollers tend to keep each other clean and thus need cleaning or fettling only at great intervals. A suitable mounting for these conveyor rollers comprises a pair of horizontal (they may be inclined) supporting rods 36 each secured to the main frame 17 by brackets 37 and screw threaded to enable the two pairs of lock nuts 38 to be employed to adjust and then lock the end bearings 39, 40 which carry the shafts 41 of the rollers 34, 35. Thus the latter can be set in relation to each other and to the roller 3 in a simple manner. These rollers 34, 35 have driving connection through gear wheels 42, 43 and 44 and a gear wheel 45 is interposed between the wheel 42 and the before named wheel 7.

In the above manner the control of the web is greatly improved, the desirable formation and treatment of very thin webs is possible without drawback and a thin web can be condensed into a thicker web or sliver to withstand further handling and conveyance.

What I claim and desire to secure by Letters Patent is:

1. In a machine for removing foreign bodies from fibre webs produced on a carding engine, the combination with a pair of hard smooth surfaced crushing rollers rotating one on the other and between which the fibre web is fed of a card clothed doffing roller, means for mounting said doffing roller for rotation on an axis parallel to that of the smooth surfaced rollers and with its surface in juxtaposition to the surface of at least one of said smooth surfaced rollers to which the crushed web normally adheres, means for driving said doffing roller at surface speed less than and in a direction opposite to that of said smooth surfaced roller from which the adhering web is to be removed, the doffing roller being disposed with the surface thereof in such close proximity to the surface of said smooth surfaced roller that by coaction of the rollers the fibre web is forced onto the card wires of the doffing roller and continuously condensed thereon to transfer the whole web from the smooth surfaced roller to the doffing roller without disruption of the web, and means for stripping the condensed web from the doffing roller at a point remote from the smooth surfaced roller.

2. A machine according to claim 1 in which the means for mounting the doffing roller in juxtaposition to one of the smooth surfaced rollers comprises movable shaft bearings with screw adjusting means for adjusting the spacing of the doffing roller with respect to the crushing roller.

3. In a machine for removing foreign bodies from fibre webs produced on a carding engine, the combination with a pair of hard smooth surfaced crushing rollers rotating one on the other of a plurality of juxtaposed side by side card clothed conveyor rollers mounted parallel with each other and disposed parallel to and immediately in advance of said crushing rollers to feed a fibre web to the nip of said crushing rollers, a card clothed doffing roller mounted on an axis parallel to and with its surface in juxtaposition to at least one of said crushing rollers to receive the web therefrom, means for driving said conveyor rollers in the same direction as and at a surface speed not faster than that of said crushing rollers and for driving said doffing roller at a speed less than and in a direction opposite to that of the crushing roller from which the web is to be removed to effect the feed of the web to and removal of the web from the crushing rollers without disruption of the web and for condensing the web on said doffing roller and means for stripping the web from the doffing roller.

4. A machine according to claim 3 in which the wire ends of the card clothing of the conveyor and doffing rollers are pointed in a direction opposite to the direction of rotation of the rollers.

LAWRENCE CROWTHER.
